UNITED STATES PATENT OFFICE

REMI J. GITS, OF CHICAGO, ILLINOIS

LUBRICATOR

Application filed March 5, 1931. Serial No. 520,313.

This invention relates to lubricators of the type disclosed in applicant's copending application for patent, Serial No. 500,523, filed December 6, 1930, and is intended for continuously or intermittently delivering measured quantities of lubricant to a plurality of conduits, each leading to a bearing or journal.

The purpose of the invention is to provide improved means for regulating the oil feed so that each bearing may receive oil only at the correct rate for such bearing, and without waste. A further purpose of the invention is to provide an improved lubricating feed device having adjustable measuring elements with control means therefor accessible from the outside of the lubricator which will enable an extremely fine feed to some of the oil conduits, such as a few drops per hour, and a much greater but definite feed to other conduits.

15 The objects of the invention are accomplished by a construction as shown in the drawings, wherein:—

Figure 1 shows the improved lubricator in front elevation.

20 Fig. 2 is a plan view of the lubricator with the cover and motor removed and partly indicated in section by the line 2—2 of Fig. 1.

Fig. 3 is a sectional view taken on the line 25 3—3 of Fig. 1.

Fig. 4 is a sectional view taken on the line 4—4 of Fig. 1.

Fig. 5 is a sectional detail of one of the oil receiving conduits and an oil lifting device 30 slidable thereon.

Fig. 6 is a fragmentary sectional view taken on the line 6—6 of Fig. 2.

Fig. 7 is a detail in plan and partly in section to illustrate the oil-receiving-conduit-adjusting means.

Fig. 8 is a sectional view of the adjusting means, as indicated by the line 8—8 of Fig. 7.

A construction by means of which this invention may be utilized comprises an oil supporting container having therein a plurality of vertically arranged oil receiving conduits, the lower ends of which conduits are coupled to conduits leading to various journals of the machine which is to be lubricated. The vertically disposed conduits within the container

are each composed of a pair of telescoping sleeves, one of which is vertically adjustable above the oil level in the container and has an inlet for receiving oil. Slidably mounted upon these conduits are oil lifting devices 55 all of which are intermittently reciprocated a uniform distance along the conduits in order to pick up a definite quantity of the lubricant and raise it so that more or less of the lubricant, so picked up, may flow into the inlet 60 openings of the conduits.

The conduits which receive the lifted lubricant are adjustable vertically independently of each other, thus varying the inlet port levels thereof, and in this manner regulating the inward flow of the lubricant therein. The ports may be of various forms and receive only a drop, or a greater quantity, of the lubricant each time the delivery elements are lifted.

These elements are further controllable by a continuous operation thereof, or intermittently at any desired rate.

Referring to the drawings, the oil container 1 is preferably a hollow casting from light metal and is provided with apertured ears 2, by means of which the lubricator is supported. The upper end of the casting 1 is open and supports the casting 3, forming a continuation thereof in carrying oil-conduit-adjusting elements 4. The upper end of the lubricator is closed by a cover plate 6. The lubricator is kept supplied with oil, at the desired level therein, by any suitable means, such as the oil receiving extension 7 formed on one end of the casting 1, and provided with a hinged closure 8 and an oil level indicating glass 9 which may be viewed through the opening 10.

A row of apertured bosses 11 are formed on the bottom of the container 1 and support oil conduits which extend upwardly therefrom to above the normal level of the oil in container 1. These conduits are formed of telescoping elements 12 and 13, the outer one 13 is adjustable vertically along the elements 12 to bring oil receiving inlets 14, formed therein, at different heights above the oil level. Above the inlets 14, the elements 13 carry fast thereto grooved collars 15. Each

of these collars is engaged by a pin 16 eccentrically carried by one of the conduit adjusting elements 4.

The heads of these elements are slotted at 5 17 to receive a screw-driver by means of which, they may be turned for the purpose of raising or lowering one of the conduit elements 13 along the conduit 12 upon which it is slidably mounted. By this means, the 10 vertical position of the openings 14 may be regulated with reference to the upper end of the stroke of oil lifting members 18 which are slidable along the conduit elements 13.

The adjusting members 4 are held to their 15 angularly adjusted positions by a spring-pressed plunger 19, Figure 7, engaging the inner toothed surface 20 of the heads 21 of members 4. The adjusting members 4 are held against longitudinal displacement by a 20 bar 22, Figure 8, fitting a groove 23 in the casting 3 and passing through grooves 24 of the adjusting elements 4. Grooves 24 preferably extend only part way around the adjusting elements, as indicated in Figure 8, 25 to limit the angular adjustment of the latter.

The oil lifting members 18, which are reciprocated along the tubes 13, have oil receiving pockets 25 at their upper ends and are provided with annular grooves 26 for 30 receiving a cross head 27. The slot 28 of the cross head, into which the lifting elements are fitted, is enlarged at 29 for receiving the lifting elements when assembled in the cross head.

35 The cross head 27 is reciprocated by shaft 30 resting upon bearing 31, Figure 3, and connected at its upper end by a coupling 31' to a short vertical shaft, not shown, but carried in the motor casing 32 and geared to 40 the motor shaft.

For the purpose of reciprocating the cross head 27 along shaft 30, the latter has a continuous right and left pitched intersecting groove or guideway 33 cut therein and engaged by a toothed pin or follower 34, Figure 3, retained in the cross head by nut 35. Rotation of shaft 30 results in a uniform reciprocation of the cross head 27 and the oil carriers 18 along the conduit elements 45 13, the amount of oil received by each of these elements depending upon the vertical adjustment thereof.

The location of openings 14 in the conduit elements 13, with reference to the uppermost position of the oil carriers 18, regulates the quantity of oil which flows from the pockets 25 into the conduits.

The bosses 11 at the bottom of oil container 1 are exteriorly threaded to have coupled 50 therewith sight feed gauges 36 to which are attached the conduits 37 leading to the bearings or journals of a machine to which the lubricant is supplied.

In the operation of the lubricator, the cross head 27 is either intermittently or continu-

ously reciprocated with uniform strokes along the conduit elements 13 by any suitable drive means, such as the motor connections illustrated in the drawings. The oil carrying devices 18 are thus regularly dipped into the lubricant and carried upwardly above the normal level of the oil in container 1. The amount of oil which flows from the pockets 25 of the lifting elements through apertures 14 in tubes 13 depends upon the vertical position of these apertures. The tubes are vertically adjusted to raise or lower the apertures and thus definitely determine the oil delivery by means of the adjusting elements 4 accessible from the exterior of container 1. 80

The elements 4 provide for a fine adjustment which is easily and quickly changed in case any bearing gets too much or too little oil. When once correctly adjusted for any particular machine, the lubricator requires 85 no further attention, except that of proper oil supply. The device requires no valves or wicks, either of which may become more or less clogged and fail to deliver at the correct rate, particularly when an extremely low 90 rate of feed of the lubricant is required.

Although but one specific embodiment of this invention has been herein shown and described, it will be understood that numerous details of the construction shown may be altered or omitted without departing from the spirit of this invention as defined by the following claims:

I claim:

1. A lubricator comprising an oil supply 100 container, said container being provided with an oil conduit vertically adjustable within said container and having an inlet for oil at its upper end, an oil carrier slidable along said conduit for carrying oil upwardly to the conduit inlet, means for reciprocating said oil carrier, and means extending to the exterior of said container for effecting vertical adjustment of the conduit. 105

2. A lubricator comprising an oil supply container, a plurality of conduits vertically adjustable within said container, and having inlets for oil at their upper ends above the normal oil level, oil carriers slidable along said conduits, means for uniformly reciprocating said oil carriers along said conduits, and means extending to the exterior of said container for effecting vertical adjustment of said conduits. 110

3. A lubricator comprising an oil supply 115 container, a conduit formed of slidably telescoping elements extending upwardly from the bottom of said container, means extending to the exterior of said container for vertically adjusting one of said elements, an oil lifting device slidable along the outer one of said elements, and means for reciprocating said lifting device along said elements. 120

4. A lubricator comprising an oil supply 125 container, a conduit formed of slidably tele-

scoping elements extending upwardly from the bottom of said container, a collar on one of said elements, means engaging said collar and extending to the exterior of said container for vertically adjusting the respective element, an oil lifting device slidale along said elements, and means for reciprocating said lifting device along said elements.

5. A lubricator comprising an oil supply
10 container, a conduit formed of slidably telescoping elements extending upwardly from the bottom of said container, a collar on one of said elements having a peripheral recess, a pin engaging said recess, means carrying
15 said pin eccentrically and extending to the exterior of said container for vertically adjusting the respective element, an oil lifting device slidale along said elements, and means for reciprocating said oil lifting de-
20 vice.

6. A lubricator comprising an oil supply container, an oil conduit vertically disposed within said container and having an inlet for oil at its upper end, an oil carrier slidale
25 along said conduit for carrying oil upwardly to the conduit inlet, a vertical drive shaft mounted within said container and having a continuous guideway therein with right and left pitched portions, a crosshead on said
30 shaft attached to said oil carrier and having a follower engaging said guideway, and means to rotate said shaft to cause reciprocation of said crosshead and oil carrier.

7. A lubricator comprising an oil supply
35 container, a plurality of conduits vertically adjustable individually within said container, and having inlets for oil at their upper ends above the normal oil level, oil carriers slidale along said conduits, means for uni-
40 formly reciprocating said oil carriers along said conduits, and means extending to the exterior of said container for effecting vertical adjustment of said conduits.

Signed at Chicago this 2nd day of March
45 1931.
